US0D1111099S

(12) United States Design Patent (10) Patent No.: US D1,111,099 S
(45) Date of Patent: * Feb. 3, 2026

(54) GAMING DISPLAY

- (71) Applicant: Aristocrat Technologies, Inc., Las Vegas, NV (US)
- (72) Inventors: Frank Rodriguez, Las Vegas, NV (US); Paul Barker, Chicago, IL (US); Charles Miller, Sr., Henderson, NV (US)
- (73) Assignee: Aristocrat Technologies, Inc., Las Vegas, NV (US)
- () Term: 15 Years
- (21) Appl. No.: 29/953,665
- (22) Filed: Jul. 23, 2024

(57) CLAIM

The ornamental design for a gaming display, as shown and described.

DESCRIPTION

FIG. 1 is a perspective view of a gaming display, showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

In these drawings, the solid lines and shading illustrate the claimed ornamental design, whereas the otherwise broken lines illustrate unclaimed environmental features and form no part of the claimed design.

1 Claim, 7 Drawing Sheets
